OUTPUT CONTROL FOR ACCORDIONS
Irving A. Cardoza, 854 Hummingbird Drive,
San Jose, Calif.

Substituted for abandoned application Ser. No. 742,296,
June 16, 1958. This application Apr. 9, 1962, Ser. No.
188,295

5 Claims. (Cl. 84—376)

The invention relates to the player control of an amplifying means for music being produced by an accordion, and this application comprises a substitution for the applicant's application Ser. No. 742,296, filed June 16, 1958, now abandoned.

Understanding that the volume of musical sounds emitted from a hand-played accordion is limited by both the size of the sound chambers of the accordion and the applied energy of the player in operating the bellows, a primary general purpose of the present invention is to provide a sound pick-up means for use with an electrically actuated sound amplifier for providing the truest possible musical output of an accordion at a controlled magnified volume and at a point remote from the accordion by a means under direct player control at the instrument.

Another object of the invention is to provide an amplifying device of the character described in which the relative amplified strengths of the notes in the treble and bass ranges may be adjustably varied by a means at the instrument.

A further object is to provide for controlling the total volume of the amplified musical output by a means at the instrument.

An added object is to provide a coordinated tremolo control at the instrument.

Yet another object is to provide all of the foregoing sound output controls in connection with a unitary attachment for existing accordion structures.

The invention possesses other objects and features of advantage, some of which, with the foregoing, will be set forth or be apparent in the following description of a typical embodiment thereof and in the accompanying drawings, in which,

FIGURE 1 is a view showing the exterior of an accordion equipped with a sound output control device embodying my invention.

FIGURE 2 is an enlarged and partly sectional longitudinal view through the device of my invention as applied to the accordion.

FIGURE 3 is a fragmentary section taken at the line 3—3 in FIGURE 2.

FIGURE 4 diagrammatically presents the essential control circuit of the pick-up and control elements of the device in combination with an associated amplifier and speaker.

The features of my invention are particularly shown as associated with an accordion 6 of a usual type essentially having a treble body side or section 7 provided with a keyboard of piano keys 8 and connected to a bass side or section 9 provided with a bank of button keys 10 by means of a usual bellows 12. The instrument sections 7 and 9 are respectively provided with usual soundbox cavities 13 and 14 respectively in which the sounds emitted from the different sets of reeds (not shown) associated with the keys 8 and 10 respectively are resonated for their escape through sound-escape grilles provided by the respective side structures; the outer side 15 of the present soundbox 13 of the treble section 7 is provided with a suitable set of grille openings 16, and the bass soundbox 14 has sound-escape grilles at its ends.

The various instrument-carried controls of my invention are particularly shown as provided on, or in association

2

with, a supplementary element 17 which is mounted as an attachment for the treble section 7 in covering relation to the grille openings 16 thereof. The present element 17 comprises an elongated body which is hollowed out from its inner side to provide a relatively narrow elongated cavity 18 and is arranged for its fixed disposal in covering opposition to the grille openings 16, said cavity being defined by mutually coterminous side walls 19 and end walls 20 extending integrally from an outer and longitudinally arched connecting outer wall 21, with the walls 19 and 20 providing a continuous flat and rectangular edge face for engaging the outer face of the accordion body wall 15 about the grille portion thereof.

The element 17 is preferably releasably secured to the accordion body section 7 as an attachment therefor by means of screws which are tapped into the body section 7 at the appropriately formed element ends 20 and may engage a suitable sound insulation gasket between the member and body, with the element preferably molded or otherwise formed of a material which is relatively non-resonant as compared with the generally resonant and sound-conducting material of usual treble and bass sections of accordions. The outer wall 21 of the element 17 mounts the present circuit-control devices in the cavity 18, whereby the element thereby functions as a supporting housing for said devices.

It will now be noted that a microphone 24 is mounted on the outer wall 21 of the control housing 17 within the space 18, while a microphone 25 is mounted in the soundbox 14 of the bass section 9, said microphones being arranged to pick up the sounds respectively emanating from the treble and bass soundboxes. In the case of the microphone 24, the same is preferably located centrally of the longitudinally arched outer housing wall 21, whereby the sound vibrations delivered into the space 18 from the treble soundbox 13 through the grille openings 16 may be delivered to this one treble pick-up microphone as a concentration of the different treble sound vibrations by wall reflection and air transmission within the cavity 18. One terminal 24' of the microphone 24 is connected to the terminal 26' of a resistor 26 mounted on the wall 21 and having a moving contact 27 carried by a control stem rotatively extending through the housing wall 21 and carrying at its outer end a positioning turnbutton 28 providing a setting pointer 28' for use in adjusting the effective resistance of the resistor by reference to suitable calibration marks on the outer housing face thereof.

The wall 21 also mounts a resistor 29 disposed within the cavity 18 and having one terminal 29' thereof connected to a terminal 25' of the microphone 25, said resistor having a moving contact 31 carried by a stem extending through the wall 21 and carrying a turnbutton 32 providing a setting pointer 32'. As indicated, the wire connections to and from the terminals 25' and 25" of the microphone 25 are conveniently extended from the bass soundbox 14 through the bellows 12 and treble soundbox 13 and through grille openings 16, and have extendable coil portions to provide for the required variable spacing of the bellows-connected instrument sections 7 and 9.

When the accordion is being played, the sound vibrations picked up by the microphones 24 and 25 are arranged to jointly produce a corresponding electric current in a common circuit for activating an amplifier-and-speaker assembly apart from the accordion and in accordance with the adjusted resistances of the resistors 26 and 29. However, since it is preferable that the net volume of sound produced from the accordion be generally constant and controllable, a means is provided in the housing 17 for automatically maintaining the sound output volume after the treble and bass outputs have been relatively adjusted, said means essentially including a potentiometer 33 provided on the housing wall 21 within the space 18

and having its moving contact arm 34 mounted on a control stem which extends through the housing top 21 and mounts a turnbutton 35 providing a setting pointer 35'.

The present control unit also includes a switch 36 for controlling a tremolo-producing circuit having its actuating means provided in unitary association with the amplifier-speaker means to be controlled, whereby to provide at the accordion all the controls customarily desirable in association with accordion-operated speakers. As indicated in FIGURE 4, the tremolo switch 36 comprises a movable contact arm 37 for engagement with a fixed contact 38 for closing a circuit thereat, with said arm carried by a rotatable stem extending through the housing wall 21 and mounting a turnbutton 39 providing a pointer 39' for indicating the conditioning of the switch.

It will now be noted that the portion of the speaker-controlling circuit provided on and in the accordion extends from the terminals of a triple-contact socket 41 provided in one end wall of the housing 17. As is brought out in the diagrammatic showing of FIGURE 4, a conductor wire 42 extends from a first contact of the connector 41 to a connection with the second terminal 25" of the bass microphone 25 through a branch 42-1, through a branch wire 42-2 to a terminal 24" of the treble microphone 24 and through a branch 42-3 to the contact 38 of the tremolo-control switch 36. Wires 43 and 44 respectively connect the other terminals 24' and 25' of the microphones 24 and 25 to the terminals 26' and 29' of the resistance elements of the resistors 29 and 26 respectively, the movable contact arms 31 and 27 of said resistors are connected by wires 45 and 46 to the different terminals of the arcuate resistance element of the potentiometer 33, and a second contact of the connector 41 is connected to the contact arm 34 of the potentiometer 33 by a wire 47. The third contact of the socket 41 is connected by a wire 48 to the switch arm 37 of the switch 36.

A three-wire extension cable 50 provides wires 52 and 57 and 58 extending from a plug 51 providing contact prongs which are respectively engageable with the terminals of the wires 42 and 47 and 48 in the connector socket 41 on the element 17. The present sound-amplifying system essentially comprises an electronic amplifier 53 represented by its casing and receiving power from the secondary of a transformer (not shown), and having its output connected to a speaker 55 by wires 56. The wires 52 and 57 of the connected cable 50 lead from the wires 42 and 47 in the socket 41 on the described accordion-carried pick-up and control unit to the amplifier to provide for the amplification by the amplifier 53 of the tonally adjusted output of the microphones for a broadcast delivery of the musical output of the accordion in player-adjusted volume and tone relations from the speaker 55, it being noted that the connected wires 42 and 52 provide a common connection in the pick-up and tremolo circuits.

It will now be noted that the extension wire 58 leading from the socket terminal for the wire 48 of the circuit of the tremolo switch 36 comprises a branch of one power input wire to the amplifier 53 and has an electric motor 61 interposed therein for actuation when the tremolo control switch 36 at the accordion is closed. The shaft 62 of the motor 61 carries a cam or eccentric 63 which is arranged to intermittently actuate a make-and-break switch 64 having a spring-loaded switch arm normally engaging a contact and arranged for its periodic displacement by the cam 63 to open the switch as the motor shaft 62 is rotated at a predetermined rotary speed. In this manner a manual closing of the switch 36 of the present unitary pick-up attachment is arranged to automatically produce a controlled tremolo effect in the output of the speaker 55 whenever desired by the operator of the accordion, it being understood that the tremolo-producing make-and-break action at the motor-

operated switch 64 might be produced by some other means than that disclosed.

Although the described accordion-mounted controls might be provided in a built-in chamber of the accordion which corresponds to that of the unitary attachment element 17, the provision of the attachment as a separate element is important for a number of reasons. Thus, the shape of the chamber 18 may be that which is best for use with a particular accordion to mount the unit and, what is more important, the resonant qualities of the material of the attachment are so much lower than that of the accordion material which defines the soundbox cavities 13 and 14 that the resonance effects of the original accordion structure are not modified, while the picked-up sounds for remote amplification may have their true tonal qualities and relations in a played musical composition.

Experiment and experience have demonstrated that the design of the present unitary amplifying combination utilizing only a single pick-up microphone disposed adjacent a music source in a housing which is sonally non-conductive has a number of marked practical advantages over the known prior practice of using a common sound-conducting housing for a plurality of pick-up microphones. Thus, the present sonically non-conductive housing prevents stray sounds from reaching the pick-up microphone and even permits a use of an accordion or similar instrument immediately adjacent the associated sound amplifier. On the other hand, the use of a single microphone from a given resonance chamber or other source disposed substantially at the geometric center, or centrally, of the housing cavity prevents the loss of sharpness of transmission due to the fact that the sound waves from a single source cannot simultaneously reach all the microphones if a receiving set thereof is being used, whereby slurring distortion occurs from the resultant loss of phase coincidence between the different microphones of a set which feeds a given amplifier from the same resonance chamber. Accordingly, for the foregoing and other reasons, the operative arrangement and features of the present pick-up unit truly provide superior results in the amplifying of such musical sounds as those arising from the playing of an accordion, for instance.

From the foregoing description taken in connection with the accompanying drawings, the advantages of the present output control for accordions will be readily understood by those skilled in the art to which the invention appertains. While I have shown and described a structure and arrangement which I now consider to be a preferred embodiment of my invention, I desire to have it understood that the showings are primarily illustrative, and that such changes and developments may be made, when desired, as fall within the scope of the following claims:

- 55 1. In combination with a musical instrument having mutually independent resonance chambers for independently produced sound vibrations from sonal vibrators within the different chambers, an electrically operative audio-amplifier means feedable by a common branched control circuit conductor having branches extending from within the different chambers, microphones associated with each said chambers for independent activation by sound waves emanating from the sonal vibrators in the different chambers to correspondingly energize different said branches of said conductor, means in said circuit branches for independently adjusting the volumetric outputs of the different microphones thereto, and a potentiometer means carried by the instrument and variably cooperative between said branches of the control circuit for adjustment by a player of the instrument for inversely varying the volumetric ratio of the combined microphone outputs delivered to the audio-amplifier means through the potentiometer and the circuit of the conductor during a playing of the instrument.
- 60 2. In combination with a musical instrument having
- 65
- 70
- 75

mutually independent resonance chambers for sound vibrations independently producible therein by sonal vibrators and each provided with a sound-discharge opening, an electrically operative audio-amplifier externally of the instrument and feedable by branches of a common conductor extending from within the confines of different chambers single and independently operative microphones unitarily associated with each of said chambers for their activation by sound waves discharged through said chamber openings, with one said microphone disposed externally of the opening from the corresponding resonance chamber and enclosed within a cavity provided by an instrument-mounted housing member of relatively non-resonant homogeneous material having an open side sealably fixed to the outer side of the outer wall of the resonance chamber to define therewith an otherwise closed sound-receiving cavity opposite said chamber opening, means mounting the enclosed said microphone centrally in said housing cavity, and a potentiometer means in said cavity providing connections of the different branches of said audio-amplifier control circuit conductor with the different said microphones.

3. The combination of claim 2 having a resistor means provided in each branch of the control circuit and disposed within the housing cavity for adjustment to independently adjust the volumetric outputs of the connected different microphones, said potentiometer means being disposed within the housing cavity and directly cooperative between said control circuit branches and the said common conductor and is adjustable to adjust the volumetric ratio of the microphone outputs delivered to the audio-amplifier means during a playing of the instrument.

4. In combination with a musical instrument having mutually independent resonance chambers for independently produced sound vibrations from sonal vibrators within the different chambers, an electrically operative

audio-amplifier means feedable by a common control circuit conductor having branches extending thereto from the different said chambers, microphones associated with the different said chambers and connected with the different said conductor branches for their independent activation by sound waves emanating from the sonal vibrators in the different chambers, and a potentiometer means connecting said circuit branches to said conductor for adjustment by a player of the instrument for varying the volumetric ratio of the portions of the microphone outputs delivered from the potentiometer to the audio-amplifier means through the circuit of the conductor during a playing of the instrument.

5. In combination with a musical instrument having mutually independent resonance chambers for independently produced sound vibrations from sonal vibrators within the different chambers, an electrically operative audio-amplifier means feedable by a common control circuit conductor having branches extending thereto from the different said chambers, microphones associated with the different said chambers and connected with the different said conductor branches for their independent activation by sound waves emanating from the sonal vibrators in the different chambers, means for independently adjusting the volumetric outputs of said microphones, and a potentiometer means connecting said circuit branches to said conductor for its adjustment by the player to inversely vary the portions of the outputs of the different microphones delivered by the potentiometer means to the audio-amplifier means through the conductor circuit.
